GARMENT HANGER

Filed Nov. 15, 1928

FRANCES R. HERZOG,
INVENTOR.

BY *Frances R. Herzog*
ATTORNEY

UNITED STATES PATENT OFFICE

FRANCES R. HERZOG, OF NEW YORK, N. Y.

GARMENT HANGER

Application filed November 15, 1928. Serial No. 319,486.

My invention relates to a new and improved garment hanger that may be used to simultaneously support a plurality of garments, such as the coat, waistcoat and trousers of a man's suit, or the coat, blouse and skirt of a woman's ensemble.

More particularly, my invention pertains to an improved method of constructing a garment hanger that will permit the same to be used to suspend the garments in otherwise inaccessible places.

It is also an object of my invention to provide a garment hanger with a new and improved means of supporting the same, the support to be useful also to receive and retain a garment without the use of extraneous retaining devices.

By my improved construction I am enabled to produce an exceedingly simple device that is adapted to cheap quantity manufacturing methods and ready assembly into a strong and durable device.

Heretofore, particularly in the construction of garment hangers intended for use in supporting the coat, waistcoat and trousers of a man's suit in an otherwise inaccessible place, for example, in the upper portion of a storage closet, the support has been affixed directly to the shaped portion that is intended to receive the coat and waistcoat. With such arrangements it becomes necessary to provide clips or other methods of suspending the trousers. Aside from unnecessarily adding to the expense of manufacture, it is generally recognized that such methods are unsatisfactory to preserve the neat and tidy condition of the trousers.

By my invention I provide a shaped coat-hanger, that may be of any of the well-known constructions it may be desired to use, and to support the same by a T-shaped member. By this arrangement, the cross-bar of the T constitutes the element across which the trousers may be hung. This is recognized as the preferable way in which to preserve the trousers in good shape ready for wear.

My invention and the other and further refinements thereof will be best understood from the following specification, and from the accompanying drawings wherein—

Fig. 1 is a plan view of my improved garment hanger;

Fig. 2 is a side elevation of my improved hanger, partly in cross-section on the line II—II of Fig. 1.

Fig. 3 is a side elevation of my improved supporting member, partly in cross-section on the line III—III of Fig. 1.

Referring to the drawings, 11 indicates the hanger for the waistcoat and coat. It will be noted that this hanger is shaped so as to fit the natural contour of the shoulder and neck portions of the coat. The hanger is provided with the usual hook 12 by which it may be suspended on a suitable rack.

Adjacent the outer edges 13 and 14 of the hanger 11 I provide a pair of vertically-extending slots 15. These slots are shaped to receive the cross-bar 16 of a T-shaped supporting member. Referring to Fig. 3, it will be seen that the cross-bar 16 is provided with a curved or arched upper surface 17, straight sides 18 and a flat bottom 19, the purpose of which will presently be described.

The trunk 20 of the T-shaped supporting member may be of any desired length, and constitutes the handle by which the hanger may be moved from place to place. It may be affixed to the cross-bar by any well-known method, but I prefer to imbed the cross-bar 16 in a groove 21 in the top of the handle 20. I intend to glue the two members together and use transversely extending screws 22. I have likewise shown this same method of the use of glue and transverse screws 23 for securing the cross-bar 16 to the coat-hanger 11.

In the use of my improved hanger with its new and improved means of supporting the same, the waistcoat and coat are fitted upon the hanger 11 and the trousers are laid across the top of the cross-bar 16. By providing the rounded portion 17 there is no danger of the shape of the cross-bar 16 being impressed upon the trousers. By the use of a bar having flat sides and bottom, the affixing of the same to the handle is greatly facilitated. By the provision of the handle, my improved hanger may be disposed in out-of-the-way places, and in any event permits the handling

of the same without danger of disturbing or mussing the garments.

Where my improved hanger is used in homes a bar or rack may be placed across the top of the closet and this space utilized for the storing of suits and other garments, which space is now usually waste space. Where my improved hanger is used in stores this same utilization of waste space is practical but an added advantage is obtained since the clerk can take several suits or garments from the racks and the trunk or handle 20 can be rested on the floor. Thus the time of the clerk will be saved in finding a suitable place to dispose of the garments during accumulation or in gathering up the accumulated garments from chairs and tables.

By the use of my improved method of supporting a coat hanger it becomes unnecessary to provide special and expensive arrangements of securing the supporting device to the central portion of the hanger, which arrangement becomes additionally expensive when a formed or shaped coat-hanger is used, and in addition interferes with the use of a proper method of suspending trousers, as outlined above.

Modifications may be made in the location and arrangement of parts within the spirit and scope of my invention and such modifications are intended to be covered by the appended claims.

I claim:

1. A garment hanger comprising, in combination, an arched member to accommodate a coat, and a support therefor comprising a cross-bar secured to the arched member and spaced therefrom so that a garment may be draped over the bar and supported thereby, the cross bar having a curved upper surface engaging the garment, a handle affixed thereto and having a groove in which the cross-bar is secured, but so arranged that the handle does not extend above the curved surface of the cross-bar.

2. A garment hanger comprising, in combination, an arched member, slots therein near the ends thereof, and a support for the arched member comprising a cross-bar secured in said slots and having a curved upper surface, and a handle having a groove in one end thereof in which the cross bar is secured.

3. A garment hanger comprising, in combination, a member having a curved and bowed portion terminating on the top thereof in an upwardly extending central portion whereby to accommodate the neck and shoulders of a coat, a hook on said member whereby the same may be suspended, and a T-shaped support having the cross bar of the T fixed to said member at either end thereof with a clearance therebetween and with the entire upper surface of the cross bar between its ends free and unobstructed so as to con-

stitute a support over which a garment may be draped to be supported thereby, and the tree of the T constituting a handle.

In testimony whereof I affix my signature.

FRANCES R. HERZOG.
